CLAIM

The ornamental design for a display panel or screen with animated graphical user interface as shown and described.

DESCRIPTION

FIG. 1 is a front view of a display panel or screen with animated graphical user interface showing the first image of our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof; and,

FIG. 8 is an eighth image thereof.

The appearance of the animated graphical user interface sequentially transitions between the images shown in FIGS. 1-8. The process or period in which one image transitions to another forms no part of the claimed design.

The outermost broken lines shown in the drawings represent a display panel or screen or a portion thereof with animated graphical user interface that are boundaries of the claimed design and form no part of the claimed design. The broken lines in the animated graphical user interface illustrating portions of the graphical user interface form no part of the claimed design.
